UNITED STATES PATENT OFFICE.

JOSEPH S. BIRD, OF HADLEY, MICHIGAN.

DOMESTIC PRESS.

SPECIFICATION forming part of Letters Patent No. 365,292, dated June 21, 1887.

Application filed March 14, 1887. Serial No. 230,857. (No model.)

To all whom it may concern:

Be it known that I, JOSEPH S. BIRD, of Hadley, in the county of Lapeer and State of Michigan, have invented certain new and useful Improvements in Domestic Presses; and I do hereby declare that the following is a full, clear, and exact description thereof, reference being had to the accompanying drawings, and to the letters of reference marked thereon, which form part of this specification, in which--

Figure 1 is a central vertical section of a barrel, showing my improved press attachment applied thereto. Fig. 2 is a cross-section of the same on line *x x*, Fig. 1. Fig. 3 is a plan view of the same with the top or cover removed.

This invention relates to improvements in domestic presses, being especially adapted and designed for keeping meats and other provisions submerged in brine or other preserving-liquid within a proper vessel.

The invention consists in the novel construction and arrangement of parts hereinafter described, illustrated in the drawings, and particularly specified in the claim.

Referring to the drawings by letters, A designates a barrel of ordinary construction adapted to hold the brine in which meats or vegetables are to be submerged. At diametrically-opposite points of the croze in the upper open end of the barrel are secured the hook B and staple C, of suitable size, and hereinafter referred to.

D designates a cross-bar of proper size to have a rod, E, play vertically through an opening in its center, which rod is held in any desired position by means of a thumb-screw, *d*, or similar fastening device, as shown. This bar D is of about equal length with the inside diameter of the barrel between the hook B and staple C, and it has on its upper edge at one end a hook-strap, B', adapted to engage the hook B, and at its other end a sliding bolt, C', for engaging the staple C.

F designates a follower-block or cover, which is of smaller diameter than the inner diameter of the barrel, and which is provided with a cross-piece, *f*, the grain of which is preferably at right angles to that of the follower, thus

strengthening the same. By means of this piece *f* the cover can be readily lifted out when desired. The cross-bar D is secured across the upper end of the barrel by means of its engagements with hook B and staples C, as shown in Fig. 1, with its upper edge or surface just below the chine of the barrel, and the rod E may then move vertically and centrally in the barrel. The follower F being placed upon the article to be kept in brine, the rod E is depressed, its lower end impinging on cross-piece *f* of the follower and depressing the latter. Sufficient pressure is exerted upon rod E to force the follower low enough to completely submerge the article in the brine, and then, before pressure is relieved from the rod, it is secured in position by means of the thumb-screw, thus firmly holding the follower in position.

G designates a cover of sufficient diameter to close the barrel, and which is provided with a central opening, *g*, through which the upper end of rod E can pass.

When it is desired to remove a piece of meat from the barrel, the bolt C' can be slid back, the bar F raised on hook B, which forms a hinge with staple B', and the follower F removed. The sliding rod E permits the proper pressure being had upon follower F, whether the barrel is full or nearly empty.

Having thus described my invention, what I claim is—

The combination, with the vessel A, having a hook, B, and staple C secured diametrically opposite each other at its upper open end, of a bar, D, provided with a hook, B', and bolt C', for engaging the hook and staple of the barrel, as described, a rod, E, moving vertically through bar D and controlled by a thumb-screw, and a follower, F, moving in the barrel and adapted to be held down by rod E, all constructed and adapted to operate substantially as and for the purpose described.

In testimony that I claim the foregoing as my own I affix my signature in presence of two witnesses.

JOSEPH S. BIRD.
